DESCRIPTION

U.S. PATENT DOCUMENTS

FIG. 1 is a right- front perspective view of a quick release snowmobile seat showing our new design;

4,779,695 A * 10/1988 Yasui 180/190
5,944,380 A * 8/1999 Atherley 297/195.1
6,264,084 B1 * 7/2001 Hayes 224/408
6,371,233 B2 * 4/2002 Ishii 180/182
6,386,630 B1 * 5/2002 Atherley 297/195.11

FIG. 2 is a left side elevational view thereof;

FIG. 3 is a rear elevational view thereof;

FIG. 4 is a front elevational view thereof;

FIG. 5 is a top plan view thereof; and,

FIG. 6 is a bottom plan view thereof.

The broken line showing of the interior of the seat is for illustrative purposes only and forms no part of the claimed design.
